UNITED STATES PATENT OFFICE.

GUY TYLER ROBERTS, OF CORONADO BEACH, CALIFORNIA.

LOCK.

SPECIFICATION forming part of Letters Patent No. 700,242, dated May 20, 1902.

Application filed January 13, 1902. Serial No. 89,541. (No model.)

To all whom it may concern:

Be it known that I, GUY TYLER ROBERTS, a citizen of the United States, residing at Coronado Beach, in the county of San Diego and 5 State of California, have invented a new and useful Lock, of which the following is a specification.

My invention relates to certain improvements in combination-locks, and has for its 10 principal object to provide a lock of simple and economical construction in which the combination may be readily changed at any time.

A further object is to provide for the locking of the bolt without subjecting any of the 15 combination members to strain.

Further objects and advantages of the invention will be apparent from a reading of the following description.

20 In the accompanying drawings, Figure 1 is a perspective view of a combination-lock constructed and arranged in accordance with my invention. Fig. 2 is an elevation of the same, partly in section, the outer side of the 25 casing being removed in order to more clearly illustrate the construction. Fig. 3 is a transverse sectional elevation of the lock on the line 3 3 of Fig. 2. Fig. 4 is a detail sectional elevation of the removable casing containing 30 the movable members of the combination. Fig. 5 is a sectional plan view of the lock on the line 5 5 of Fig. 2. Fig. 6 is a detail perspective view of the casing of the lock, one of the sides being removed. Fig. 7 is a detail 35 perspective view of the casing for carrying the combination-dogs and their connected operating devices. Figs. 8, 9, 10, and 11 are detail views of portions of the mechanism referred to more specifically hereinafter. Fig. 40 12 is a detail view of one of the combination-dogs.

Similar numerals of reference are employed to designate corresponding parts throughout the several figures of the drawings.

45 10 indicates a suitable casing divided by a partition 11 into two compartments, one of which is adapted to receive a casing 12, in which the combination-dogs and their operating mechanisms are supported and guided. 50 The lower portion of the casing 12 is divided by a series of parallel vertical partitions 13 into a number of guiding openings or slots

14, in which are placed dog-carrying frames 15, each of which is adapted to receive a combination-dog 16, there being as many guiding-slots and dogs as may be required to form the desired combination. In the present instance I employ four combination-dogs for a four-number combination, and each dog is adjustable, so that the combination may be 60 changed to any possible combination to the numbers "1" to "8," inclusive, arranged in four separate rows. Extending across the front face of the casing is a locking-slot 16', formed by notching each of the partitions 13, and in 65 each side of the rectangular locking-dogs is a notch which may be brought into alinement with the locking-slot by manipulating the finger-piece 18 of its carrying-frame. The notches in the locking-dogs are designated, 70 respectively, 20, 21, 22, and 23, and each is arranged at a different distance in the length of the sides of the dogs. The position of the notches may be best described by assuming the dog to be about nine inches square 75 and divided by lines placed at equidistant intervals throughout its surface and dividing the dog into a number of lines, of which there would be eight at each edge of the dog. The notch 20 would then be formed at the 80 first divisional line, so that in one position with respect to the slot 16' it would have a value of one and in the reverse position a value of eight. The slot 21 on another edge of the dog would be so situated as to have a 85 value either two or seven. The third notch, 22, would be so placed as to have a value of three or six, and the remaining notch, 23, would be so situated as to have a value of four or five. In this manner it is possible to 90 change each dog so that it will require from one to eight movements of the carrying-frame to bring it to position in alinement with the locking-slot.

The upper portion of the casing 12 is formed 95 of three metallic plates 24, 25, and 26, secured together at their upper ends and spaced for a distance sufficient to permit the entrance of the finger-pieces 18 and the upper portions of the dog-carrying frames, two of such finger-pieces and frames being disposed in each of the spaces formed by the plates, the finger-pieces projecting laterally beyond said plates in convenient position for manipula-

tion. The two outer plates 24 and 26 extend from the top of the lower portion 12 of the casing to the upper point of connection, while the central plate 25 terminates at a point 5 some distance above the top of the lower portion 12 in order to form a space, as indicated at 27 in Fig. 4, to permit the bending of the upper portions of the dog-carrying frames, which are guided between the plates 25 and 10 26. The plate 26 is perfectly plain; but in each of the plates 24 and 25 there are formed two zigzag slots 28 of the construction best illustrated in Figs. 1 and 3, and into these slots project small pins 29, carried by the finger-pieces 18. The walls of the slots are rectangular, so that abrupt square shoulders may be formed to retain the pins 29 in any position to which they may be adjusted, and in operation the finger-pieces are moved to 15 and from to travel the pins in their respective slots, and so move the combination-dog to the desired positions, and, if desired, suitable indicating-marks may be placed along the plates to indicate the proper position of 20 25 the combination-dogs.

Projecting from the lower portion of the lock-casing 10 is a sleeve or casing 31, in which is guided a longitudinally-movable locking-bolt 32, the inner end of which projects without 30 in the lock-casing and is provided with two transversely-disposed locking-notches 33 and 34, in either of which an arm 35 will engage to hold the bolt firmly in locking or unlocking position. The slot 33, in which the arm engages 35 when the bolt is in locking position, is comparatively narrow and is so arranged with respect to the longitudinal movement of the bolt as to assume a position in alinement with the inner wall of the casing, so that on 40 the entrance of the locking-arm the latter will serve to lock the bolt to the inside of the casing, thus avoiding any injurious straining on the arm should it be attempted to force the bolt outwardly. When in the locking 45 position, as indicated in Fig. 2, an arm 37 on the locking-bolt is arranged in contact with the upper surface of a small lug or shoulder projecting from one side of the cylinder or casing 12 and serves to lock the same in position when the bolt is in locking position.

Pivoted on a stud 40 in the upper portion of the casing are two arms 41 and 42, connected by a cross-brace 43, the outer end of the arm 41 being secured to or formed integrally with a U-shaped rod 44, one end of which extends down within the casing at a point between the wall and the cylinder or casing 12 and the opposite end being disposed outside the casing and provided with a finger-piece 45 and catch 46, which may be engaged above a lug 47 or below a second lug 48 to lock it in either elevated or depressed position. The lower end of the arm 42 fits within a small longitudinal slot 49, formed on the upper face 60 of the bolt member 32, so that when the combination members have been moved to un-

locking position the bolt may be reciprocated by manipulating the finger-piece 45.

Pivoted on a stud 50 is a latch member 51, having at its upper end a latch-bar 52 of a width equal to that of the cylinder or casing 12 and adapted when the combination-dogs have been moved into proper position to enter the slot 16', the bar first passing through a suitable slot or opening 53, formed in the 70 partition 11 in alinement with the cylinder-slot. The locking-arm 35, which has been previously described, is also secured to the stud 50 and moves with the latch, so that when the combination-dogs have been moved in 80 such manner as to present their notches in alinement with the notch 16' the latch-bar may enter under the influence of a suitable spring 55 and move the locking-arm from position in the groove of the bolt. The latch-bar is moved out from the cylinder-notch and the locking-arm is moved into the bolt-groove by a lug or finger 56, carried by and projecting from the end of the bolt and adapted to come into contact with the lower end of the 90 latch as the bolt is moved to the locking position. The bolt may also be locked or held in the unlocked position by causing the locking-arm to move into the second groove 34, this being effected by providing the latch with 95 a link 57, the outer end of which passes through an eye 58 on the lower portion of the arm 42, the parts being so constructed that when the finger-piece 45 is pulled down and the arm 42 is moved to project the bolt the 100 eye 58 on the lower end of said arm will come into contact with the enlarged head of the link, pulling the latch-bar from engagement with the cylinder-slot and at the same time forcing the locking-arm into engagement with 105 the groove 34. This movement permits of the withdrawal of the combination cylinder or casing for the purpose of changing the combination, the latter being readily altered by removing one or more of the dogs and changing their positions in order to bring a different notch in alinement with the casing-slot. The bolt may be held in the out or unlocked 110 position by engaging the catch 46 of the finger-piece under the lug 48 on the casing. 115

In order to prevent injury to the latch in event of any attempt to remove the combination-casing while the device is locked, the latch is always held out of engagement with the locking-slot by the footpiece 56 of the 120 bolt, and the cylinder is confined in place by the locking-arm 37 engaging with the lug 38, as previously described. As there is some danger of bending the arm 37 during the attempt to remove the casing, I provide on the 125 inner face of the casing a lug 60, which engages with the upper edge of the arm and prevents any upward movement of the same. The lugs 38 and 60 are arranged in different vertical planes, so that there will be no interference when the casing is withdrawn after 130 the arm 37 has been first moved to unlocked

position. On the side of the removable casing is formed a lug or shoulder 61 to fill the space not occupied by the arm 44, sufficient space being left for the free movement of said arm, so that the bolt can be readily moved.

The lock forming the subject of the present invention may be employed for any purpose, and the bolt 32 may be connected or serve as a connection between any parts which it is desired to lock together; but in the preferred form of the device I employ the bolt as a means for moving a locking-arm 70 to open and close positions.

Secured to or formed integral with the outer end of the sleeve 31 is a casing 71, in one end of which is secured a curved arm 72, terminating at its opposite end in a pocket-piece or keeper 73, the inner walls of the latter being provided with any desired number of grooves 74, each of a width adapted to receive the head 75 of the movable arm 70. The relative diameters of the interior of the keeper and the head 75 are such that should any attempt be made to force the arms apart the slightest lateral movement will cause the head to engage in one or other of the slots, and thus lock the two parts firmly together, and the head of the keeper may be round, square, or of other form best suited for the purpose.

30 The arm 70 is pivoted within the casing 71 on a suitable pin 75, and its extreme inner end is slightly reduced in diameter and adapted to fit within a suitable opening or recess 76, formed in the outer end of the locking-bolt, and the movement of the locking-bolt serving to oscillate the arm 70 on its pivot-pin, the two arms separating for an extent sufficient to permit the entrance of an article to be locked.

40 The device is especially adapted for use as a bicycle-lock, the two arms 70 and 72 being locked around the tire and felly of one of the wheels or other moving parts of the machine and the casing being provided with a suitable clamp 78, by which the lock may be secured at a convenient point on the frame of the machine.

While the construction herein described and illustrated in the accompanying drawings is the preferred form of the device, it is obvious that many changes in the form, proportion, size, and minor details of construction may be made without departing from the spirit or sacrificing any of the advantages of my invention.

Having thus described my invention, what I claim is—

1. In a lock, a plurality of interchangeable dogs having notches, a bolt-controlling latch adapted to enter the same, and means for independently operating said dogs to move them into locking and unlocking positions, said dogs being removably supported by said operating means.

65 2. In a lock, a plurality of reversible combination-dogs having notches, a bolt-controlling latch adapted to enter the same and

means for independently moving said dogs to locking and unlocking positions.

3. A combination-dog comprising a reversible polygonal plate having in each of its edges an unlocking-notch, and a carrier in which said dog may be adjusted to present any one of the notches in alignment with the bolt-controlling means.

75 4. A combination-dog comprising a reversible polygonal plate having on each of its edges a single notch arranged in such relation that a notch representing any desired numeral may be adjusted for coöperation with the bolt-controlling mechanism, and mechanism for supporting and adjusting said plate.

5. In a lock, a plurality of combination-dogs, carrying-frames therefor, finger-pieces secured to each of said frames, and means 85 for holding said frames in any position to which they may be adjusted.

6. In a lock, a plurality of combination-dogs, carrying-frames therefor, finger-pieces secured to said carrying-frames, guiding-plates having shouldered slots, and pins carried by the frames and adapted to said slots.

90 7. In a lock, a plurality of combination-dogs, bolt-controlling mechanism adapted to coöperate therewith, a series of carrying-frames for said dogs, finger-pieces and pins carried by said frames, and guiding-plates having zigzag slots for the reception of said pins.

8. In a lock, a plurality of combination-dogs, bolt-controlling mechanism adapted to coöperate therewith, carrying-frames for said dogs, finger-pieces and pins carried by said frames and guiding-plates having slots for the reception of said pins, each of said slots 105 being arranged to form a series of seating-recesses for the pins, substantially as specified.

95 9. In a lock, the combination of the lock-casing, bolt-controlling mechanism arranged therein, a bolt, a removable casing extending within the main casing, means for locking said removable casing within the lock-casing when the bolt is in locking position, a series of combination-dogs guided by said removable casing and coöperating with the bolt-controlling mechanism, and means for operating said dogs.

10. In a lock, the combination of the lock-casing, bolt-controlling mechanism arranged therein, a bolt, a removable casing extending 120 within the main casing, means for locking said removable casing within the lock-casing when the bolt is in locking position, a plurality of combination-dogs guided by said removable casing and coöperating with the bolt-controlling mechanism, carrying-frames carried by the removable casing and supporting said dogs, slotted guiding-plates arranged above and removable with the removable casing, and finger-pieces secured to the carrying-frames, said carrying-frames having pins for engagement in the slots of the guiding-plates.

11. In a lock, the combination of the lock-casing, a bolt and bolt-controlling mechanism

arranged therein, a removable casing carried by the lock-casing, a series of partitions arranged in said cylinder and having alining notches for the reception of an element of the bolt - controlling mechanism, combination-dogs arranged within the spaces between the partitions, an independent carrying - frame for each of said dogs, finger-pieces carried by said frames, projecting pins extending from 5 said frame, slotted guiding-plates arranged on the upper portion of the removable casing, the pins being adapted to enter said slots and be locked therein in an adjusted position.

12. In a lock, the combination of the lock- 15 casing, a partition therein dividing said lock-casing into two compartments, a bolt and bolt-controlling mechanism disposed in one of said compartments, a removable casing having a projecting lug or boss, a locking-finger 20 carried by the bolt for engagement therewith, a series of locking-dogs carried by the removable casing and means for independently adjusting said dogs, substantially as specified.

13. In a lock, the combination with a bolt, 25 of means for effecting the longitudinal movement of the same, a locking-arm adapted to engage with and hold the bolt at both extremes of movement, a latch secured to and movable with the locking-arm, a combination- 30 controlled device for permitting the movement of the latch and arm to unlocking position, and means controlled by the bolt for moving said latch out of contact with the combination-controlled device when the bolt is 35 moved to locked and unlocked position.

14. In a lock, the combination with a manually-operated bolt, of a combination device comprising a series of movable elements each having a notch, a latch adapted to move into 40 the series of notches when the latter are in alinement, a locking-arm operably controlled by the latch for locking said bolt at both extremes of movement, and means controlled by the bolt and its connected parts for moving said latch away from the notches when the bolt is moved to locking or unlocking position.

15. The combination with a manually-operated bolt having a locking-slot, of a combination device comprising a series of movable elements each having a notch, a pivoted latch independent of the bolt and adapted to move into the series of notches when the latter are in alinement, a locking-arm operatively connected to the latch and movable therewith to unlock the bolt, and an engaging finger carried by said bolt and adapted to engage with the latch to move the locking-arm into engagement with the locking-slot of said bolt, substantially as specified.

16. In a lock, the combination with a movable bolt having a pair of locking slots or notches, a locking - arm adapted to engage therewith, a combination device comprising 65 a series of movable elements each having a

notch, a pivoted latch carrying the locking-arm and adapted to move into the series of notches when the latter are in alinement, a pivoted lever connected to the bolt, and a link connecting said lever to the latch and adapted to move the latter from the notches and to force the locking-arm into engagement with the bolt when the latter is moved to unlocking position.

17. In a lock, the combination with a movable bolt having a pair of locking slots or notches, a locking - arm adapted to engage therewith, a combination device comprising a series of movable elements each having a notch, a pivoted latch carrying the locking-arm and adapted to move into the series of notches when the latter are in alinement, a spring adapted to operate on said latch, a pivoted lever connected to the bolt, a secondary lever connected to and movable with said pivoted lever, a U-shaped arm extending from the secondary lever to a point outside the lock - casing, a finger - piece arranged at the end of said arm, holding-lugs for said finger-piece, a link connecting the pivoted lever to the latch and adapted to move the same from the notches and to force the locking-arm into engagement with the bolt when the latter is moved to unlocking position, and a finger carried by the bolt and also adapted to operate on said pivoted latch, substantially as specified.

18. In a lock the combination of the lock-casing, a bolt and bolt-operating mechanism contained therein, a removable casing carried by the lock-casing and containing a combination device adapted to coöperate with the bolt-controlling mechanism, lugs formed on the adjacent faces of the removable casing and lock-casing, and a locking arm or finger carried by the bolt and adapted to pass between said lugs.

19. In a device of the class specified, a grooved keeper, a bolt adapted thereto, means for operating said bolt, the engaging end of the bolt being provided with a head or tip of a width less than the width of the grooves of the keeper.

20. In a device of the class specified, a stationary semicircular member having a keeper at its outer end, a lock-casing carrying said member, a bolt adapted to the casing, means for moving the bolt, a movable semicircular member pivoted to the lock-casing and in engagement with the bolt, the opposite end of said movable member being adapted to engage in the keeper of the stationary member.

In testimony that I claim the foregoing as my own I have hereto affixed my signature in the presence of two witnesses.

GUY TYLER ROBERTS.
